ATTYS.

UNITED STATES PATENT OFFICE.

FREDERICK C. OVERBURY, OF HILLSDALE, NEW JERSEY, ASSIGNOR TO THE FLINT-KOTE COMPANY, OF BOSTON, MASSACHUSETTS, A CORPORATION OF MASSACHUSETTS.

ROOF.

Application filed December 22, 1921. Serial No. 524,103.

This invention relates to roofs, more particularly of that type wherein the roof covering is composed of sheet material such as is commonly formed by treating felt or other fibrous material with asphalt, with or without a surface coating of ground slate or other granular material. Even when as is usual this material is cut into separate rectangles or "shingles", or is cut and laid in 10 overlapping courses of strips it presents a comparatively flat appearance, due to the thinness of the material, which is often objectionable. This effect is further heightened by the substantial uniformity in its 15 color.

This invention provides a construction whereby a much more substantial appearance is produced with this material and by which a variegated color effect may be produced by using a double coated sheet, the 20 coatings being of different colors on the two sides, and by laying so that each color appears at suitable places.

By this construction symmetrical patterns such as hexagons, or the like, may be formed, each being complete in a single color and two colors of such pattern appearing through all the sheets of the roof.

The roof may be constructed in panels cut 30 and folded to produce the required designs which may be laid in units, or it may be embodied in strips each having a single line of fold and superposed. The strip form permits the laying of the designs in more 35 than one color relation, while with the panel construction such relation is fixed. The strip construction permits the laying of a complete design with the laying of each strip, instead of only half the design as in 40 the usual strip form, thus permitting the roof to be laid faster than with the ordinary form.

For a more complete understanding of 45 this invention, together with further objects and advantageous details and arrangements, reference may be had to the accompanying drawings in which—

Figure 1 is a plan of a sheet of roofing cut crosswise to make a panel having three 50 complete rows of shingle design.

Figure 2 is a plan of a sheet cut lengthwise to make a panel having two complete rows of the design.

Figure 3 is a perspective of the form shown in Figure 1 partly folded to form the 55 panel.

Figure 4 is a plan of the completed panel.

Figure 5 is a section on line 5—5 of Figure 4.

Figure 6 is a section on line 6—6 of 60 Figure 4.

Figures 7 and 8 are perspectives showing assemblies of cooperating single folded strips to produce different color relations 65 of the design.

Referring to Figures 1, 3, and 4 a sheet of roofing is indicated at 1 having thereacross a plurality of series of interrupted cuts, each cut, as shown, comprising a portion 2 extending laterally of the sheet and portions 70 3 extending in diagonal relation from the ends of the portion 2. The outer ends of the cuts 3 which converge from adjacent cuts 2, are connected by uncut portions 4 about which the material of the strip may be 75 folded, the portions 4 as shown being substantially in alignment across the sheet. Between adjacent series of cuts is a continuous fold line 5. The sheet is bent on itself alternately in opposite directions about 80 the hinge lines 4 and 5 as shown in Figure 3, the portion below the lowest hinge line 4 being bent under and carrying therewith the tabs 6 bounded by the meeting cuts 2 and 3. This causes the under side of each tab 6 to 85 appear as shown in Figure 3 while the cut edges in the section between the hinge line 4 and the line 5 next above define an upper margin identical in shape to the tab 6, but reversed in position to form in the construction shown a hexagonal pattern presented by the reverse side of the sheet. The cut edges form also the outline of the lower half of the complementary pattern in the upper layer of each fold, the other half being 90 formed by the margin of a succeeding overlying tab 6. The sheet is folded forwardly along the line 5 to bring the cuts 2 of the next succeeding course against the cuts 2 of the lower course. The material above this 95

100

second hinge line 4 is then folded backwardly, the tabs 6 of this course projecting down to the edge of the cut line 2 of the lower course. The sheet is similarly bent 5 back and forth in alternate directions about succeeding hinge lines 4 and 5 to the full extent of the sheet. When the folded portions are brought close together, a panel is produced having the design shown in Figure 10 4, wherein alternate vertical rows of the design are formed by opposite sides of the sheet. As shown a lower uncut piece of roofing 7 having its lower edge in alinement with the lower edges of the tabs 6 may be 15 positioned under the lower fold to finish the lower edge of the roof. Referring to Figures 5 and 6, it is seen that the hexagonal designs are formed on the outer faces of the folded sections along line 5—5 of Figure 4, 20 while the designs along the section 6—6 are formed of portions appearing through cut-outs in the upper sections and which are from the reverse side of the sheet. If desired each of the surfaces of the sheet may 25 be faced with coating material such as slate and may, if desired, be of different shade or color, in which case the design will alternate in vertical rows having the colors of the two sides. A pattern is thus presented 30 lengthwise of the lines of fold.

The lower or butt edges of each of the overlying courses is thus of double thickness, the upper layer of which is recessed back from its line of fold to expose areas of 35 the lower layer and the lower layer has tabs extending downwardly beyond the fold line complementary to the recesses of the upper layer and forming continuations of the areas of the lower layer exposed through the recesses. 40

In Figure 2 is shown a similar construction in which instead of cutting and folding the sheet widthwise it is cut and folded lengthwise. In the ordinary commercial 45 sheet sizes, a pair of series of cuts may be employed with this method of procedure, the panel itself being of any required length. When the fold is crosswise of the sheet the width thereof is determined by the width of 50 the sheet while the length, extending in direction from the eaves to the ridge pole of the roof, may be as desired.

Instead of forming the material in panels it may be cut in strips, either lengthwise or 55 crosswise of the sheet, embodying substantially the width between the two fold lines 5 of the panel, this construction being indicated in Figures 7 and 8. These strips are folded along the uncut portions 40 in the 60 same manner as the panels are folded along the uncut portions 4. In this construction a single row of designs is formed by the cuts, the surface of the under layer of the material forming this pattern while the outer surface, or that of the upper layer furnishes 65

one half of the complementary pattern. Here, if desired, the two sides of the strips may be of different shades or colors so that alternate designs of different colors may appear in the finished roof. In the case of the 70 strips, however, one strip may be superposed on an adjacent strip in a manner to bring two designs of the same color in vertical alinement as shown in Figure 7, or they may be offset laterally to bring designs 75 of opposing color in vertical columns as shown in Figure 8. In this latter arrangement zigzag lines of designs alternating in color are formed across the roof. While as shown the cuts are composed of portions extending laterally of the sheet and portions connected thereto on diagonals, which construction forms hexagonal designs in the roof, it is evident that the cuts may be otherwise formed if desired and that unlike but 80 complementary designs may be formed in alternation.

Having thus described certain embodiments of this invention it should be evident that many changes and modifications might be made therein without departing from its spirit or scope as defined by the appended claims.

I claim:

1. A structure of the class described comprising a sheet of double faced roofing cut through at intervals thereacross, the portions between said cut portions serving as 95 hinges about which the sheet may be folded back on itself, said cuts being so related to the line of fold as to cause portions of the surface on the inside of the fold to show from the outside when the sheet is in position on the roof.

2. A structure of the class described comprising a sheet of double face roofing cut through at intervals to form one half the outline of a design, the portions between said cut portions serving as hinges about 100 which the sheet may be bent back on itself, the half of the design on the under layer projecting beyond the hinge portions and the mating cut edge in the upper layer defining the opposite half of the design on said under layer whereby the complete design is presented on the surface of the under side of the fold and one half of the complementary design is defined on the opposite side of the sheet presented by the portion bent back.

3. A structure of the class described comprising a sheet of roofing having interrupted cuts therein, the interruptions forming hinge portions about which a portion of said sheet may be folded back against another portion thereof, said cuts being so related to the line of fold that a pattern is presented when said sheet is folded, parts of said pattern being formed by opposite sides of said sheet.

4. A structure of the class described com-

prising a sheet of double surfaced roofing having interrupted cuts therein, the interruptions forming hinge portions about which a portion of said sheet may be folded back

5 against another portion thereof, said cuts being so related to the line of fold that a pattern is presented when said sheet is folded, parts of said pattern being formed by opposite sides of said sheet so presenting 10 both surfaces.

5. A structure of the class described comprising a double surfaced sheet of roofing of different colors on opposite sides, said sheet having interrupted cuts therethrough, the 15 interruptions forming hinge portions about which a portion of said sheet may be folded back against another portion thereof, and said cuts being so related to the line of fold that a varicolored pattern is presented when 20 said sheet is folded, parts of said pattern being formed by opposite sides of said sheet.

6. A roofing panel composed of a sheet of double surfaced roofing material having a plurality of series of interrupted cuts extending thereacross, and hinge portions intermediate adjacent series of cuts about which said sheet may be folded back on itself, the interruption between said cuts also forming hinge portions about which the 30 sheet may be folded back on itself, said sheet being folded alternately in opposite directions about said hinge portions, and said cuts being so formed that when a sheet is so folded a pattern is presented comprising 35 portions of each of said surfaces.

7. A roofing panel composed of a sheet of double surfaced roofing material having its opposite faces of different color, having a plurality of series of interrupted cuts extending thereacross, and hinge portions intermediate adjacent series of cuts, about which said sheet may be folded back on itself, the interruption between said cuts also forming hinge portions about which the 40 sheet may be folded back on itself, said sheet being folded alternately in opposite directions about said hinge portions, and said cuts being so formed that when the sheet is so folded, a two colored pattern is 50 presented comprising portions of each of said surfaces.

8. A roofing panel comprising a sheet of roofing material folded on itself alternately in opposite directions and cut at intervals 55 adjacent to a line of fold through one layer only to show the surface of underlying portions thereof.

9. A roofing element comprising weather-proof sheet material interruptedly cut and folded upon itself to provide an upper and a lower layer, one of said layers having portions projecting beyond the line of fold.

10. A roofing element comprising weather-proof sheet material interruptedly cut and folded upon itself to provide an upper and 65

a lower layer, one of said layers having portions projecting beyond the line of fold, and the other layer having edge portions cut back of the line of fold.

11. A roofing element comprising weather-proof sheet material interruptedly cut and folded upon itself to provide an upper and a lower layer having portions projecting beyond the line of fold.

12. A roofing element comprising weather-proof sheet material interruptedly cut and folded upon itself to provide an upper and a lower layer having portions projecting beyond the line of fold, and the upper layer having recesses through which the lower 80 layer is exposed.

13. A roofing element comprising weather-proof sheet material interruptedly cut and folded upon itself to provide an upper and a lower layer, the upper layer being recessed 85 from said line of fold to expose areas of the lower layer therethrough, and the lower layer having portions extending beyond the line of fold.

14. A roofing element comprising weather-proof sheet material interruptedly cut and folded upon itself to provide an upper and a lower layer, the upper layer being recessed from said line of fold to expose areas of the lower layer therethrough, and the lower 95 layer having portions extending beyond the line of fold and forming continuations of said exposed areas.

15. A roofing element comprising weather-proof sheet material interruptedly cut and folded upon itself to provide an upper and a lower layer, the upper layer being recessed from said line of fold to expose areas of the lower layer therethrough, and the lower 100 layer having portions extending beyond the line of fold and forming continuations of said exposed areas.

16. A roofing element comprising weather-proof sheet material folded alternately in 110 opposite directions along spaced lines to produce a series of overlapping courses of double thickness, the upper layer of each double thickness being recessed to expose areas of the lower layer of the same course. 115

17. A roofing element comprising weather-proof sheet material folded alternately in opposite directions along spaced lines to produce a series of overlapping courses of double thickness, the upper layer of each course 120 being recessed back from its lower edge fold to expose areas of the lower layer of the same course.

18. A roofing element comprising weather-proof sheet material interruptedly cut and folded alternately in opposite directions along spaced lines to produce a series of overlapping courses of double thickness, the upper layer of each course being recessed to expose layers of the same course, and the 125 130

lower layer having portions extending below the upper layer.

19. A roofing element comprising weatherproof sheet material interruptedly cut and folded alternately in opposite directions along spaced lines to produce a series of overlapping courses of double thickness, the upper layer of each course being recessed

back from its lower edge fold to expose areas of the lower layer of the same course, and the lower layer having portions extending below said line of fold and forming continuations of said exposed areas.

In testimony whereof I have affixed my signature.

FREDERICK C. OVERBURY.
